UNITED STATES PATENT OFFICE.

NATHAN KATZIN, OF WINSTON-SALEM, NORTH CAROLINA.

AMUSEMENT DEVICE.

Application filed July 3, 1926. Serial No. 129,512.

This invention relates to amusement devices, and more particularly to a device intended for use in connection with a device simulating a radio cabinet having provision for selectively indicating questions and indicating answers for the same, the said device preferably employing dials such as are used for tuning dials of radio sets.

It is the purpose of this invention to provide novel means for moving current controlling elements during the manipulation of an indicator of the device, locating the question which the user wishes to ask, and to provide a switch operable in connection with the circuit control independently movable, and having means associated with it pointing to the answer of the question propounded.

It is a further object of this invention to provide means for establishing a circuit through a lamp which is intended to denote that the pointer has been directed to the answer to the question.

It is a still further object of this invention to produce a device of the character indicated which will operate in a manner embodied in the process of tuning a radio, a condition which will prove to be amusement incident to its use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in elevation of a case;

Figure 2 illustrates an end view thereof;

Figure 3 illustrates a sectional view on the line 3—3 of Fig. 4;

Figure 4 illustrates a view in elevation of the interior of the case just rearward of the battery; and

Figure 5 illustrates a sectional view of the device on the line 5—5 of Fig. 4.

In these drawings, 10 denotes a casing which is rectangular in plan and it may have a lid or cover 11 hinged at the top thereof, and the said casing may also be provided with a longitudinally extending partition 12, although this is a detail of

construction that may be changed to suit particular requirements. A battery 13 is located in the casing from which conductors 14 and 15 extend in order that a circuit may be established, as will presently appear. The front panel 16 of the casing is provided with dials 17 and 18 with relation to which tuning disks or knobs 19 and 20 are rotatable, respectively. A lamp socket 21 extends through the panel and a lamp 22 is supplied to the socket, and the terminal or contact of the lamp is intended to be engaged by a switch element or terminal 23, to which the conductor 15 is connected. The lamp socket has an arm 24 electrically connected to it at the rear side of the panel and the arm is intended to bear against the face of a toothed wheel 25, which toothed wheel acts as a conductor in the lamp circuit, as will presently appear.

The wheel 25 is rotatable on a spindle or shaft 26 which is journaled in the front panel, and the said spindle is rotatable with the knob 20 of the dial 18. The wheel 25 has an insulating disk 27 on its face, and the spindle extends through the said insulating disk. A switch contact 28 extends through the insulating disk and the contact is embedded or connected to the wheel 25. An insulating bushing 29 is rotatable with the spindle 26 and a brush 30 is also carried by the bushing and is movable therewith so that when the brush is moved over the insulating disk 27 to a sufficient degree, it will engage the contact switch 28 and establish a circuit, as will presently appear.

A tie bar 31 is connected at or near one of its ends to the bushing and the bushing rotates in an aperture of the tie bar with the brush 30 in electrical engagement with the tie bar. The knob or disk 19 of the dial 17 is associated with a spindle or shaft 32 that is rotatable in the panel and in the tie bar, from which tie bar, however, it is insulated, and the said spindle or shaft has a gear wheel 33 mounted on it, that meshes with the teeth of the gear wheel 25, and hence, as the gear wheel 33 is rotated, the gear wheel 25 will rotate on the shaft or spindle 26 without moving the said shaft or spindle 26.

The invention contemplates the provision of an indicia bearing element 34 such as a card, which may have apertures to form clearances for the dials, and the areas on the cards around the dials are preferably

divided into a plurality of radially disposed spaces 35 and 36 on the respective dials. The spaces 35 are intended to be supplied with indicia or questions, whereas the spaces 36 may contain answers to questions, the questions and answers being indiscriminately arranged in order that there will be more or less uncertainty with respect to the answers to the questions. The disk 19 is supplied 10 with a pointer or indicator 37, and the disk 30 is supplied with an indicator or pointer 38.

In operation, the disk 19 will be manipulated by a player and the indicator 37 will 15 be moved to the question which he wishes to ask, and thereafter, the disk 20 will be rotated until the brush 30 engages the electrical switch or contact 28 when a circuit will be established, lighting the lamp, at which 20 occurrence the pointer 38 will be located at a space that shall be regarded as the answer to the question. The disk may then be arbitrarily reset, and since the gearing may be turned independently of the switch brush 25 30 and the relation of the contact 28 with respect to the switch 30 may be at different locations on different adjustments, there will be more or less chance as to where the pointer 38 will be located with respect to the 30 answers at the time the lamp is illuminated.

I claim:

1. In an amusement device, a casing, rotatable wheels mounted for movement in unison, an operating member by which one 35 of the wheels is rotated, a pointer on said operating member, question spaces with relation to which the indicator is operable, a rotatable element on which the other wheel is rotatable, means for manipulating the rotatable element including an indicator, a plurality of answer spaces with relation to which the indicator is operative, an electrical circuit including a lamp, and means for controlling the circuit through the manipulation of the last mentioned manipulating 40 means.

2. In an amusement device, a casing, rotatable wheels mounted for movement in

unison, an operating member for rotating one of the wheels, a pointer on said operating member, question spaces with relation to which the indicator is operable, a rotatable element on which the other wheel is rotatable, an insulating disk on the last mentioned wheel, a conductor connected to the wheel and exposed on the face of the insulating disk, means for rotating the said rotatable element including an indicator, a brush moved by the rotatable element for engaging the conductor on the insulating disk, 60 an electric lamp socket electrically connected to one of the wheels, a lamp contact in operative relation to the socket, a source of electricity and conductors connected to the contact and electrically connected through the conductor on the wheel with the said lamp socket.

3. In an amusement device, a casing, rotatable wheels mounted for movement in unison, an operating member by which one 70 of the wheels is rotated, a pointer on said operating member, question spaces with relation to which the indicator is operable, a rotatable element on which the other wheel is rotatable, means for manipulating the rotatable element including an indicator, insulating bushings on the operating member and the rotatable element, a tie bar on the said insulating bushings, a source of electricity connected to the tie bar, a lamp 80 socket, a lamp contact in operable relation to the socket, a conductor from the source of electricity to the contact, a conductor from the lamp socket to one of the 85 wheels, an insulating disk on one of the wheels, a brush mounted on the rotatable element and movable over the insulating disk, a brush contact extending through the insulating disk and electrically connected to the wheel on which the insulating disk is mounted whereby when the rotatable element is turned, the brush will engage the contact, and a plurality of answer spaces with relation to which the indicator is operative.

NATHAN KATZIN.
